ABSTRACT: A releasable ski pole strap construction having frangible means attached at one end to the apertured ends of a ski strap and at the other end to means disposed within the ski pole handgrip, the frangible means being adapted to release the strap when such receives a skier-disabling impact force. The frangible means may comprise a wire link of "figure-8" shape, the loops of said link being disposed in planes located at right angles to each other, one loop being engageable with the apertured ends of the ski strap, the other loop being engageable with the attaching means in the handgrip, the loops of the link being adapted to open up on sustaining a skier-disabling impact force. Alternatively, the frangible means may comprise a plastic strip attached at one end to the ski strap and at the other end to the attaching means in the handgrip, the strip being adapted to break upon sustaining a skier-disabling impact force.

RELEASABLE SKI POLE STRAP

BACKGROUND OF THE INVENTION

This invention relates to ski poles of the type used by skiers and, more particularly, to ski poles of the type in which the wrist engaging strap is separable from the pole upon sustaining a sudden impact or otherwise excessive force that might cause injury to the skier.

The usual ski pole construction comprises a shaft or pole of metal or bamboo having a handgrip at its upper extremity and a snow penetrating point or spike at its lower extremity. A disc or basket is mounted on the pole adjacent the point to limit the penetration of the pole into the snow, and a wrist engageable strap is usually attached to the upper end of the pole or the handgrip to secure the pole to the skier's wrist.

The strap is necessary to prevent accidental loss of the pole; however, it has frequently been the cause of serious injury to the skier. If the basket on the pole should catch on an obstruction, such as a root, rock, branch of a tree or even become tangled with another skier, the ski pole can severely injure the skier's wrist, arm, or shoulder since the strap unyieldingly anchors the pole to the wrist.

Accordingly, a number of releasable ski strap constructions have been heretofore proposed. These straps have been designed to accomplish the necessary and usual function of attaching the pole to the wrist, while being able to separate from the pole upon being subjected to an excessive force, thereby to prevent injury to the skier. However, such constructions have not been entirely successful. They have been relatively complicated and consequently, expensive. As a result, the majority of ski poles in use today are unequipped with releasable strap means, thereby to constitute a continuing threat to the safety of skiers.

It is thus the primary object of the present invention to provide a releasable ski pole strap construction that will be simple and economical to construct and will thus find ready acceptability by skiers everywhere.

SUMMARY OF THE INVENTION

The releasable ski strap construction of the present invention comprises frangible means attached at one end to the ends of a ski strap member and at the other end to means disposed within the ski pole handgrip, such frangible means being adapted to release the strap member upon receipt of a skier-disabling impact force. The frangible means may desirably comprise a "figure-8" link, the loops of the link being disposed in planes located at right angles to each other, one such loop being engageable with the ends of the strap member, the other loop being engageable with the attaching means in the handgrip, at least one of the loops being adapted to open up on sustaining an excessive force.

Alternatively, the frangible means may comprise a plastic strip attached at one end to the strap member and at the other end to the attaching means in the handgrip, the strip being adapted to break upon sustaining an excessive force.

BRIEF DESCRIPTION OF THE DRAWINGS

FIG. 1 is a side elevational view, partly in section, of the handgrip and wrist strap assembly of the present invention in place on the upper extremity of a ski pole.

FIG. 2 is another embodiment of a ski pole suitable for use with the present invention.

FIG. 3 is an enlarged view of a "figure-8" wire link suitable for use as the frangible means in the improved ski strap constructions of FIGS. 1 and 2.

FIG. 4 is a side elevational view of another embodiment of the present invention in which the frangible connecting means comprises a plastic strip.

FIG. 5 is an enlarged view of the strip of FIG. 4.

DETAILED DESCRIPTION OF THE PREFERRED EMBODIMENTS

Referring to the drawings and in particular to FIG. 1, the upper extremity of a tubular ski pole is indicated by the numeral 10. A molded elongated tubular handgrip 12 of rubber or plastic is snugly fitted over the upper extremity of the pole 10, and the usual wrist strap for attaching the pole to the wrist of the skier is indicated by the numeral 14.

As shown in FIG. 1, the pole 10 is conically tapered as at 16 and the ends 18 of the strap 14 are furnished with a grommet 20 which provides two apertures 22 in the strap 14. Alternatively and as shown in FIG. 2, the pole 10 may be provided with a wood insert 24 in the upper extremity 26 thereof to receive a threaded fastener 28 passing through the handgrip 12.

The present invention contemplates the provision of frangible means between the grommetted apertures 22 in the ends of the strap 14 and either the conically tapered end 16 of the pole of FIG. 1 or the fastener 28 of the pole of FIG. 2.

In the embodiment of FIG. 1 such frangible means comprise a "figure-8" link 30 which joins the grommetted apertures 22 to the conically tapered end 16 of the pole 10. The link 30 may desirably be made of 14 gauge plated steel wire annealed so that the loops 32 thereof will open up upon sustaining an axial force of approximately 30 pounds. As can be seen from FIG. 3, the two loops 32 are rotated so that their planes are located at right angles to each other. Thus one loop 32a passes through the apertures 22 and the other loop 32b is received upon the conically tapered end 16 of the pole 10, the handgrip 12 fitting over the entire assemblage with the strap 14 passing through a slot 34 therein in the usual manner.

In the embodiment of FIG. 2, the link 30 joins the apertures 22 in the strap 14 with the fastener 28, one loop 32a passing through the apertures 22 and the other loop 32b being received on the fastener 28.

In both embodiments if an excessive or impact force be applied to the strap 14, either one or both of the loops 32 will merely open up, thereby to release the strap 14 from its engagement with the attaching means in the handgrip 12 (the conically tapered end 16 of the pole 10 in FIG. 1 or the fastener 28 of the pole of FIG. 2) and avoid injuring the skier. Obviously, although the link 30 has been stated as being desirably constructed from an annealed wire the loops 32 of which will open upon sustaining a moderate axial pull (of 30 pounds), the link may be made of a lighter gauge wire should a lesser fail-safe load be desired, as for a child's pole.

An advantage of the "figure-8" link type of frangible means illustrated in FIGS. 1 and 2 is that the link 30 may easily be repaired after a loop 32 opens up merely by use of a pair of pliers.

An alternative embodiment is illustrated in FIGS. 4 and 5. The frangible means therein illustrated comprises a plastic strip 40 having two apertures 42, 44, one in each end. One of the apertures 42 is designed to fit over the attaching means in the handgrip 12, that is, either over the conically tapered end 16 on the pole 10 illustrated in FIG. 1 or on the fastener 28 in the type of pole construction illustrated in FIG. 2. The other aperture 44 is sandwiched between the ends 18 of the strap 14 being retained by the grommet 20. Should an excessive or impact force be sustained by the strap 14 in an amount that might cause injury to the skier, the strip 40 merely breaks in two.

I claim:

1. A releasable ski pole strap construction comprising: an elongated tubular handgrip member adapted tightly to receive a ski pole therein; a wrist engageable strap member having apertures at both ends, said strap member being folded so that said apertures are in register and adjacent said handgrip member; means disposed within said handgrip member and adapted to attach said strap member to said pole; and

frangible means attached at one end to said apertured ends of said strap member and at the other end to said attaching means, said frangible means being adapted to release said strap member when said strap member receives a skier-disabling force.

2. The ski pole of claim 1 in which said frangible means comprises a figure-8 link, one loop of said link being engageable with said apertures in said strap member, the other loop of said link being engageable with said attaching means in said handgrip member.

3. The ski pole of claim 2 in which said loops are rotated so that their planes are at right angles to each other.

4. The ski pole of claim 2 in which said link is a wire link, at

least one of said loops being adapted to open up when said strap member receives a skier-disabling force.

5. The ski pole of claim 1 in which said frangible means comprises a plastic strip, said strip being adapted to break when said strap member receives a skier-disabling force.

6. The ski pole of claim 5 in which said plastic strip comprises two apertures, one in each end, said plastic strip being attachable by means of one aperture to said apertured ends of said strap member, said plastic strip being attachable by means of the other aperture to said attaching means in said handgrip member.
